DESIGN FOR A SHIRT

Abb S. Curtis, Fort Worth, Tex., assignor to A. G.
Spalding & Bros. Inc., New York, N. Y., a cor-
poration of Delaware

Application September 12, 1939, Serial No. 87,156

Term of patent 3 $\frac{1}{2}$ years

To all whom it may concern:

Be it known that I, Abb S. Curtis, a citizen of the United States, residing at Fort Worth, in the county of Tarrant and State of Texas, have invented a new, original, and ornamental Design for a Shirt, of which the following is a specification, reference being had to the accompanying drawing, forming a part thereof, and in which:

Figure 1 is a front view of the complete shirt.

Fig. 2 is a fragmentary rear view of the shirt.

That portion of the back not shown in Fig. 2 is conventionally plain.

The characteristic feature of my design resides in the combination, on the shirt disclosed, of the specific contrasting bands arranged on the front and rear, as shown.

I claim:

The ornamental design for a shirt, substantially as shown and described.

ABB S. CURTIS.
